(57) **CLAIM**

The ornamental design for a cooking appliance, as shown and described.

DESCRIPTION

1. Cooking appliance

1.1 : Perspective

1.2 : Front

1.3 : Back

1.4 : Left

1.5 : Right

1.6 : Top

1.7 : Bottom

1.8 : Perspective view 2

1.9 : Top view 2

The broken lines depict portions of cooking appliance that form no part of the claimed design; reproduction 1.8 is a perspective view showing the state of use that the main body of the claimed design has been tilted; reproduction 1.9 is a top view showing the state of use that the display has been operated; the display shown in reproduction 1.9 and not in any other views is unclaimed subject matter that appears only in the use state. This design is for a cooking appliance that can stir-fry, roast, deep-fry, boil, wok-hei, etc.; the upper half-circle part on the top of the cover is the display part, and the lower half-circle part is made of transparent material, so that the user can check the cooking status of the food at the inside pot; as shown in reproduction 1.8, the main body can be tilted to cook the inside food evenly.
